(57) **CLAIM**

The ornamental design for a tubular beam, as shown and described.

DESCRIPTION

FIG. 1 is a top perspective view of a tubular beam incorporating my new design;

FIG. 2 is a right side view thereof;

FIG. 3 is a left side view thereof;

FIG. 4 is a front elevation view thereof;

FIG. 5 is a rear elevation view thereof;

FIG. 6 is top plan view thereof;

FIG. 7 is a bottom plan view thereof; and,

FIG. 8 is a bottom perspective view thereof.

The broken lines shown in the drawings illustrate portions of the tubular beam that form no part of the claimed invention. The tubular beam is shown with a symbolic break in its length. The appearance of any portion of the article between the break lines forms no part of the claimed design.
